UNITED STATES PATENT OFFICE.

JOHN HENRY MANN, OF SYRACUSE, NEW YORK.

DESIGN FOR A TROLLING-SPOON.

Specification forming part of Design No. 5,291, dated September 26, 1871.

To all whom it may concern:

Be it known that I, JOHN HENRY MANN, of Syracuse, in the county of Onondaga and State of New York, have invented a new and original Design in Trolling-Spoons; and I do hereby declare that the following is a full, clear, and exact description of the same, reference being had to the annexed drawing making a part of this specification, and to the letters and figures of reference marked thereon.

The drawing is a representation of a set of trolling devices, showing nature of my invention.

My invention has relation to trolling-spoons for fishing purposes, and consists as follows:

The spoon is lettered A in the accompanying drawing. It is shaped like a shield, being rounded at its lower part and shouldered at b. The upper end tapers to a point, from which projects the bent

loop c, by means of which it is held on the wire d. The surfaces of the shield are rounded, rendering it concavo-convex or spoon-shaped. The convex surface is polished, and the concave surface painted in some suitable bright color.

I claim as my invention—

The design for trolling-spoons, in which the spoon A is of a shield-shape, having shoulders b, and formed with the concavo-convex or spoon surfaces, as described.

In testimony that I claim the above I have hereunto subscribed my name in the presence of two witnesses.

JOHN HENRY MANN.
